US0D1090586S

(12) **United States Design Patent** (10) Patent No.: **US D1,090,586 S**
(45) Date of Patent: ** Aug. 26, 2025

(54) **DISPLAY SCREEN OR PORTION THEREOF WITH GRAPHICAL USER INTERFACE**

(71) Applicant: **Panasonic Holdings Corporation**,
Osaka (JP)

(72) Inventors: **Takumi Tonoike**, Osaka (JP); **Motoshi Anabuki**, Hyogo (JP); **Seiya Imomoto**, Tokyo (JP); **Yusuke Kushiki**, Osaka (JP)

(73) Assignee: **PANASONIC HOLDINGS CORPORATION**, Osaka (JP)

(**) Term: **15 Years**

(21) Appl. No.: **29/921,022**

(22) Filed: **Dec. 14, 2023**

(30) **Foreign Application Priority Data**

May 18, 2023 (JP) ..... 2023-010075 D
May 18, 2023 (JP) ..... 2023-010076 D

(51) **LOC (15) Cl.** **14-04**

(52) **U.S. Cl.**

USPC **D14/485**

(58) **Field of Classification Search**

(57) **CLAIM**

The ornamental design for a display screen or portion thereof with graphical user interface, as shown and described.

DESCRIPTION

The sole FIGURE is a front view of a display screen or portion thereof with graphical user interface, showing our new design.

The outermost broken line rectangle in the drawing illustrates a display screen or portion thereof and forms no part of the claimed design. The remaining broken lines in the drawing show portions of the graphical user interface and form no part of the claimed design.

1 Claim, 1 Drawing Sheet
